(57) **CLAIM**

The ornamental design for a display screen with graphical user interface, as shown and described.

DESCRIPTION

The sole FIGURE is a front view of a display screen with graphical user interface in accordance with the invention. The outermost broken lines show environmental structure and an electronic device having a display screen and do not form any part of the claimed design. The remaining broken lines show portions of the graphical user interface that form no part of the claimed design.

1 Claim, 1 Drawing Sheet
